UNITED STATES PATENT OFFICE.

GEORGE B. SNOW, OF LONG BEACH, CALIFORNIA, ASSIGNOR TO SNOW DENTAL COMPANY, OF BUFFALO, NEW YORK, A CORPORATION OF NEW YORK.

DENTAL ARTICULATOR.

1,160,114.

Specification of Letters Patent.

Patented Nov. 9, 1915.

Application filed June 29, 1915. Serial No. 37,034.

To all whom it may concern:

Be it known that I, GEORGE BURWELL Snow, a citizen of the United States, and a resident of the city of Long Beach, in the county of Los Angeles and State of California, have invented certain new and useful Improvements in Dental Articulators, of which the following is a specification, reference being had to the accompanying drawing, in which—

Figure 1 represents a dental articulator to which my improvements have been applied. Fig. 2 is an enlarged view, in section, showing the internal construction of my spring cushion. Fig. 3 shows a modified form of my spring cushion, in which a flat spring is substituted for the spiral spring shown in Fig. 2. Fig. 4 is a lateral view, showing the upper and lower model supports of the articulator in part, with the incisal stay rod and its platform, attached to the upper and lower model supports respectively, the platform being capable of rotation upon the lower model support. Fig. 5 is a lateral view of a platform, made in two sections; one being attached to the model support, with the platform proper attached thereto and capable of lateral rotation upon it, as shown in Fig. 6. Fig. 6 is a front view of the platform shown in Fig. 5. Fig. 7 is a sectional view of the same platform. Figs. 8, 9 and 10 show a modified form of the platform.

This invention is an improvement upon the dental articulator described and claimed in the United States Patent No. 870,909, issued November 12, 1907.

I have found that in the use of this articulator, that unless it is carefully handled, the upper and lower model supports are apt to be sprung together, and the articulation of the dentures under construction thereby deranged. I have therefore added the well known incisal stay rod, having improved upon the ordinary method of mounting it by making its platform adjustable in inclination, as will be hereinafter described. I have also interposed spring cushions in the joints of the articulator for the purpose of imitating the directly lateral movement of the mandible in the direction of the inter-condyloid line, which it is well to take into account when constructing artificial dentures.

In the articulator shown in Fig. 1, the lower section is not directly connected to the

upper one, but slotted links are interposed between the two sections which swivel vertically in sockets in the ends of the upper section, and are held in position by gripping devices. Joint pins, attached to the arms of the lower section, pass into the slots in these links, having longitudinal movement therein, and the articulator is thus rendered capable of imitating the lateral movements of the mandible with a fair degree of accuracy. The interposed link, referred to above, is shown at 9, Figs. 1 and 3. The inclination of these links is varied at times upon the two sides of the articulator, as the movements of the condyles vary in their inclination in different patients, and are not always alike on the two sides of the same head. (The above description applies to the articulator shown in Patent No. 870,909, as well as the one described herein). The upper section carries its model support 3, and the lower section its model support 4; both being made of round wire, bent to the required shapes. To the upper model support is firmly attached the arm 5, having a vertical hole at its free extremity, through which passes the incisal stay rod 6, secured by the set screw 7. The lower end of the stay rod rests upon the inclined platform 8, which is attached to the lower model support 4. Whenever the inclination of the links 9 is varied, the inclination of the platform 8, which is attached to the lower model support 4, should be correspondingly varied; but it usually forms an integral part of the model support; which is cast instead of being formed of round wire, and its inclination cannot, therefore, be changed. As I show it, it is a separate part, having a cross hole 12, through which the wire is passed which forms the model support before it is bent into the required shape; the two parts being attached by means of soft solder. If a very fusible alloy is used for this purpose, the union may be broken by a heat much below that of boiling water, and the parts will become re-united when they cool; and in this way, the platform may be rotated vertically upon the model support and given any inclination desired. This platform is shown at 8, Fig. 4. By using easy flowing solder for connecting the parts, I am enabled to dispense with set screws or gripping devices, which, in this place, would be cumbersome and objectionable.

The path followed by the point of the incisal stay pin 6 upon the platform 8, will be V shaped, the point of the V to the front; the V being compounded of two circular arcs, the centers from which they are struck being in the articulator joints on either side, the curved faces of the links 9 allowing circular movements of one section of the articulator upon the other. When there is a considerable difference in the inclination of the two links 9, I meet it by giving the platform a lateral inclination as shown in Figs. 6 and 8; thus making the V shaped path of the incisal stay pin more precipitous on one side and less so on the other. For this purpose, I show at Fig. 5, a platform similar in general outline to 8, Figs. 1 and 4, but divided into two sections, 10 and 11. Section 10 contains the cross hole 12 which receives the lower model support 4, and has upon its side a pintle 13, upon which is fastened the section 11. This is shown in central vertical section in Fig. 7. Fig. 6, is an end or front view of the same platform, and it is shown in dotted lines as tilted laterally upon the pintle 13. The parts are to be connected by the same easy flowing solder used for attaching the platform to the model support, and so by slightly warming them, they may be loosened and adjusted to any desired inclination, vertically or laterally.

In Figs. 8, 9 and 10, the pintle 13 is shown as extending through the platform 11, and threaded for the thumb nut 14, which holds the parts securely, and so the lateral adjustment may be effected without disturbing the vertical one.

There is a direct lateral movement of the condyles of the mandible in the glenoid fossa in a way; which so far as I am aware, has not been shown in any articulator heretofore constructed. For the purpose of imitating this movement, I use the spring cushions which are constructed as follows. (See Fig. 3.) The cheek piece 16, presents a flat surface to the link 9, allowing of an easy sliding movement of one part upon the other, and the joint pin 17 is received into the slot 18 in link 9. A cup 19, is threaded 50 into the arm 15 of the lower section 2 of the articulator, and into this is received the cup 20, formed upon the back of the cheek piece 16; the two parts fitting closely, but allowing easy movement. A spiral spring 21 occupies the cavity formed by the telescoping of the two cups 19 and 20, which forces the cheek piece 16 inward against the link 9. A screw 22 passes centrally through the spiral spring, and is threaded into the cheek piece 60 16, its head 23, shouldering against the outer surface of the cup 20. This screw limits the

action of the spiral spring 21, so that the cheek piece 16 is barely out of contact with the curved face of link 9, allowing easy movement of one upon the other, without lateral shake. A steady pin 28 prevents the rotation of the cheek piece 16 and holds it level. By lateral pressure upon either one of the links 9, the opposing one of the two cheek pieces 16, which is pressed against, will yield, allowing a directly lateral movement, the parts recovering their original positions as soon as pressure is released. And in this way I am enabled to imitate the slight lateral movement which is executed by the mandible during mastication, heretofore mentioned.

In Fig. 3 is shown an alternative construction of the spring cushion in which a flat spring is substituted for the spiral spring shown in Fig. 2. A cup 26 forms an integral part of the arm 15, and through it passes an extension of the cheek piece 16, threaded at its end. A nut 25 limits the movement of the flat spring, which is attached to the lower section 2 by the screws 27. The operation of the device is precisely the same as that of the one shown in Fig. 3.

Having thus described my inventions, I claim as follows.

1. In a dental articulator, a platform for an incisal stay rod, rotatable vertically upon the model support; substantially as described.

2. In a dental articulator, a platform for an incisal stay rod, made in two sections, one section rotatable vertically upon the model support, the other section rotatable laterally upon the first section, substantially as described.

3. Spring cushions interposed between the two sections of a dental articulator and forming parts of the joints thereof, said cushions affording a direct lateral movement along the intercondyloid line, substantially as set forth.

4. A spring cushion interposed in the joint of a dental articulator, consisting of a hollow cylindrical bearing surface attached to one section of the articulator, a cylindrical cup moving longitudinally therein, and attached to a vertically flat cheek piece, which carries the pintle of the articulator joint, a spring, forcing the cup inward against the other part of the joint, and a screw bolt to regulate and limit the movement of the spring; substantially as described.
